ham, Germany

Application January 23, 1934, Serial No. 707,964
In Germany January 24, 1933

6 Claims. (Cl. 173—13)

This invention relates to a method of manufacture of stranded conductors of the so-called "re-entrant type". A conductor of the "re-entrant type" may be defined as a stranded conductor in which each one of the wires of which it is composed changes its position in the cross section of the conductor, in such a manner that it passes in a regular sequence from the centre of the cross section of the conductor to the outer periphery, from which it returns again to the centre. The individual wires are surrounded by an insulating oxide layer or a thin layer of lacquer. Such stranded conductors have the advantage that even when traversed by currents of high frequency the current density is uniform in all parts of the cross section of the conductor and the latter is therefore free from the skin effect which increases the resistance. Such conductors are thus suitable for the transmission of currents of high frequency and may, for instance, be employed as conductors in cables intended for carrier frequencies.

In the accompanying drawing:

Figure 1 illustrates one method of stranding conductors according to the invention.

Figure 2 illustrates a second method.

Figure 3 illustrates a third method and

Figure 4 illustrates a stranded conductor as in Figure 3 but in the finished stage.

Referring to Figure 1, three single conductors 1, 2, 3 are stranded together into a strand 4 and three such strands 4 are combined together to a strand of higher order 5, three of which are, in their turn, further stranded into a stranded conductor 6. As will be seen from Figure 1, each wire changes its position in the cross section of the conductor in the manner hereinbefore referred to. Such a stranded conductor has a bad filling factor which can be improved only by subjecting the completely stranded conductor to a drawing or rolling process. As a result of the high mechanical stresses thereby required breakages often occur in the individual wires. In order to maintain the conducting connection, the wires have to be soldered, which is detrimental to the conductor and increases its cost of manufacture.

According to the invention, during the manufacture of the stranded conductor, profile strands of a thermoplastic material are inserted at suitable places between the individual stranded elements and are stranded therewith. The thermoplastic material has to be sufficiently solid at ordinary temperature to withstand the mechanical stresses of the stranding. A stranded conductor according to the invention may, for

instance, be produced by making individual wires, for instance all wires 1, of a thermo-plastic material instead of making all the wires of metal which is conducting. However, other methods of stranding are to be preferred, as will herein-after be referred to. If a stranded conductor with thermo-plastic layers interposed therein according to the invention is subjected to a drawing or rolling process and heat is simultaneously applied thereto, the strands consisting of thermo-plastic material will soften, and owing to the gaps thereby produced, it will be possible to impart to the stranded conductor a higher filling factor without a greater expenditure in mechanical energy.

Instead of using two conductors with one strand of thermo-plastic material to form a stranded element of a higher order, as shown in Figure 1, use is preferably made of a larger number of individual conductors, for instance five or six, which are stranded together around a core of thermo-plastic material. However, other modes of stranding are possible in which a stranded conductor according to the invention is rendered suitable for rolling or drawing, by inserting between the stranded elements thermo-plastic profile strands which are rendered plastic under the action of heat and change the mechanical rigidity of the stranded conductor in a radial direction.

It has, for instance, been found that the available space can be especially well utilized by a method of stranding, which is illustrated in Figure 2. Three stranded elements 11 are laid around a central wire 10, each of which stranded elements 11 consists of a core of thermo-plastic material 12, around which six conducting wires 13 have been stranded.

A further suitable method of stranding is illustrated in Figure 3. Six profile strands 20 of thermoplastic material are laid around a wire 21 constituting the core; around this central part there are laid six further stranded elements, each of which consists of a core of thermo-plastic material 22, around which six individual wires 23 have been stranded. Thus the whole of the stranded conductor thereby obtained comprises thirty-seven conducting wires.

In order to produce a conductor of more than thirty-seven wires, three or six stranded elements may be laid around a central wire, each of which stranded elements consists of a structure, such as shown in Figure 2 or 3.

The completely stranded conductor is heated

and is drawn by rolling or application of pressure.

Figure 4 is a cross section through a stranded conductor according to Figure 3 after it has been subjected to a rolling process. The thermo-plastic material has, as will be seen, filled up completely the spaces between the conducting wires, thus serving at the same time as an insulation between the wires. If a stranded conductor built up as hereinbefore described, is used for deep sea submarine cables, the further advantage is attained that the thermo-plastic material serves at the same time as a pressure-equalizing means.

The profile strands used according to the present invention, may consist of any thermo-plastic insulating material used in the electrical art, for instance guttapercha, "Paragutta", balata etc. Especially advantageous is polystyrol, since this material can be drawn into rigid strings or bands and in addition thereto, it possesses especially good electrical properties.

Further, mixtures of polystyrol, with guttapercha, balata, Paragutta or the like, are used for the profile strands.

25 Instead of using thermo-plastic profile strands as hereinbefore described, according to a further modification of the invention, use is made of an intermediate layer of a soluble substance, so that instead of subjecting the stranded conductor to heat treatment, it can be treated by means of a solvent. For instance, it is possible to dissolve intermediate layers of guttapercha before the rolling or drawing process, by means of benzol.

What I claim is:

35 1. A method of manufacturing a high frequency stranded conductor of the type in which each strand is insulated from the next, and the strands change relative positions to minimize skin effect, consisting in inserting profile strands of an insulating thermoplastic material between the stranding elements of the stranded conductor and stranding them therewith, softening the said profile strands after the stranding and subjecting the stranded conductor to pressure in such a way 40 that the profile strands are distributed between the stranding elements.

2. A method of manufacturing a high frequency stranded conductor of the type in which each strand is insulated from the next, and the strands change relative positions to minimize skin effect, consisting in inserting profile strands of an insulating thermoplastic material between the stranding elements of the stranded conductor and stranding them therewith, softening the said 50 profile strands by heat after the stranding and

subjecting the stranded conductor to pressure in such a way that the profile strands are distributed between the stranding elements.

3. A method of manufacturing a high frequency stranded conductor of the type in which each strand is insulated from the next, and the strands change relative positions to minimize skin effect, consisting in inserting profile strands of an insulating soluble material between the stranding elements of the stranded conductor and stranding them therewith, softening the said profile strands by means of a solvent after the stranding and subjecting the stranded conductor to pressure in such a way that the profile strands are distributed between the stranding elements. 15

4. A method of manufacturing a high frequency stranded conductor of the type in which each strand is insulated from the next, and the strands change relative positions to minimize skin effect, consisting in stranding around a central core a plurality of strands, each comprising a core of thermoplastic material around which there is stranded a layer of conducting wires, softening all the said profile strands, after the stranding of the strands around the said central core, and subjecting the entire stranded conductor to pressure in such a way that the profile strands are distributed between the stranding elements. 20

5. A method of manufacturing a high frequency stranded conductor of the type in which each strand is insulated from the next, and the strands change relative positions to minimize skin effect, consisting in inserting profile strands of polystyrol between the stranding elements of the stranded conductor and stranding them therewith, softening the said profile strands of polystyrol after the stranding, by heat, and subjecting the stranded conductor to pressure in such a way that the profile strands are distributed between the stranding elements. 30

6. A method of manufacturing a high frequency stranded conductor of the type in which each strand is insulated from the next, and the strands change relative positions to minimize skin effect, consisting in inserting profile strands of polystyrol 35 mixed with insulating thermoplastic material between the stranding elements and stranding them therewith, softening the said profile strands of polystyrol mixed with insulating thermoplastic material after the stranding, by heat, and subjecting the stranded conductor to pressure in such a way that the profile strands are distributed between the stranding elements. 45
